DESIGN FOR A COMBINED LAVATORY AND PEDESTAL

John M. Lewis, Abingdon, Ill., assignor to
Abingdon Sanitary Manufacturing Company,
Abingdon, Ill., a corporation of Illinois

Application July 12, 1940, Serial No. 93,592

Term of patent 7 years

To all whom it may concern:

Be it known that I, John M. Lewis, a citizen of the United States, residing at Abingdon, in the county of Knox and State of Illinois, have invented a new, original, and ornamental Design for a Combined Lavatory and Pedestal, of which the following is a specification, reference being made to the accompanying drawing, forming a part thereof.

In the drawing,

Fig. 1 is a perspective view of a combined lavatory and pedestal embodying my new design;
Fig. 2 is a plan view; and
Fig. 3 is a front elevation thereof.

I claim:

The ornamental design for a combined lavatory and pedestal, substantially as shown.

JOHN M. LEWIS.
